(57) CLAIM

The ornamental design for a target support, as shown and described.

DESCRIPTION

FIG. 1 is a front perspective view of a target support showing our new design;

FIG. 2 is a front side view thereof;

FIG. 3 is a back side view thereof;

FIG. 4 is a left side view thereof;

FIG. 5 is a right side view thereof;

FIG. 6 is a bottom view thereof;

FIG. 7 is a top view thereof; and,

FIG. 8 is a back perspective view thereof.

The broken lines in the drawings form no part of the claimed design. The broken lines of the archery target in FIGS. 1, 2, and 8 are illustrative of environment and form no part of the claimed design. The broken lines of the arrow in flight and the tubular support stand in FIG. 8 are illustrative of environment and form no part of the claimed design.

1 Claim, 6 Drawing Sheets
